UNITED STATES PATENT OFFICE.

CHARLES B. HOY, OF CINCINNATI, OHIO.

FOLDING BOX.

Application filed November 3, 1921. Serial No. 512,618.

To all whom it may concern:

Be it known that I, CHARLES B. HOY, a citizen of the United States, residing at Cincinnati, in the county of Hamilton and

5 State of Ohio, have invented certain new and useful Improvements in Folding Boxes, of which the following is a specification.

My invention relates to improvements in folding boxes. One of its objects is to provide a cardboard extension box such as those 10 extensively employed for candies and toilet articles by a folding operation from stamped and scored blanks adapted to be shipped flat or in knocked-down condition. Another 15 object is to provide an improved folding type of box having the strength and rigidity of built up types of boxes. Another object is to provide an improved blank for folding boxes, as for instance of standard proportions, adapted to be set up and used by a 20 variety of users. Another object is to provide an improved blank for folding boxes adapted to receive its exterior finish in the flat, as for instance by printing designs 25 thereon. Another object is to provide improved means to reinforce all or a portion of the walls to resist the strain of packing and transporting heavy substances in the boxes. Another object is to provide improved 30 means to lock the boxes in their set-up position to enable them to resist the weight of heavy articles without being crushed or distorted. Another object is to provide an 35 improved type of blank from which cardboard boxes having extension edges are 40 adapted to be produced by a folding operation. Another object is to provide an improved type of blank for cardboard boxes which is reinforced and strengthened by 45 extension edges and adapted to be shipped flat and set up by a folding operation at the point where it is required to be filled. Another object is to provide an improved type 50 of blank for cardboard boxes from which either full telescopic extension boxes or half telescopic boxes are adapted to be formed by a 55 folding operation. My invention also comprises certain details of form, combination and arrangement, all of which will be 60 fully set forth in the description of the accompanying drawings in which:

Fig. 1 is a plan of an improved type of blank from which my improved boxes are adapted to be formed by a folding operation.

55 Fig. 2 is a plan of the blank folded in position for shipment.

Fig. 3 is a perspective view of a folding skeleton box adapted to be employed where it is desired to provide extension shoulder or partially telescopic boxes.

60

Fig. 4 is a plan detail, showing a modification of the blank Fig. 1.

65

Fig. 5, is a perspective view of one of the box sections folded complete at one end and partially folded at the opposite end.

Fig. 6 is an enlarged sectional detail through a full telescopic extension box, taken on line 6—6 of Fig. 9.

70

Fig. 7, is an enlarged sectional detail through a partially telescopic or shoulder extension box.

Fig. 8, is a vertical section taken on line 8—8 of Fig. 7.

Fig. 9, is a perspective view of the exterior of a full telescopic extension box complete.

75

Fig. 10 is a perspective view of a partial telescopic or shoulder extension box complete.

Fig. 11 is a plan of one end of a blank 80 for a relatively wide box illustrating a modification of Fig. 1.

Fig. 12 is a view similar to Fig. 11 illustrating another modification.

Fig. 13 is a perspective view of a member 85 employed to reinforce and add interior finish to the box where required.

Fig. 14, is a sectional detail taken on line 14—14 of Fig. 11, after folding.

Fig. 15, is a sectional detail taken on line 90 15—15 of Fig. 12, after folding.

The accompanying drawings illustrate the preferred embodiments of my invention in which Fig. 1 illustrates the plan of a blank 95 from which either the lid section or the container section of the box is adapted to be formed by a folding operation. Where a partially telescopic or shoulder box, such as shown in Figs. 7 and 8 is to be produced both the bottom or container section and the 100 top or lid section may be produced from blanks of the same dimensions. Where boxes of full telescopic type such as shown in Figs. 6 and 9 are to be produced certain dimensions of the blank for the upper or lid section are greater than corresponding dimensions of the blank for the lower or container section in order that the lid section 105 may telescope over the container section.

Assuming that Fig. 1 represents the 110 blank for the lid section of a box, 15 represents the top or main portion of the lid, 16

and 17 and 16' and 17' represent the side forming portions which are united to the sides of portion 15 by means of portions 18 and 19 which are bound or outlined by the 5 scored lines 20 and 21, and by the cuts 22 to enable the portions 18 and 19 to be folded face to face upon the under side of the edges of portion 15 and to which they are preferably firmly glued to thereby form the 10 sides of the extension 24 of the lid. The side sections or members 16' and 17' are designed to have paste or glue applied to the face thereof as indicated by the shading in Fig. 1, and to then be folded upon and 15 pasted to the inner faces of side sections 16 and 17 to strengthen and reinforce the sections 16 and 17 and also to present a rounded and finished edge in place of a cut edge where the fold is made along the scored 20 line between sections 16 and 17 and sections 16' and 17'. This pasting and folding operation is preferably done on a pasting machine before the blank is shipped out. The portions 16 and 17 and 16' and 17' after 25 pasting and in the set-up position to form the lid, extend outwardly from the portion 15 at substantially right angles thereto as shown in Fig. 5, but for shipment the portions 16 and 17 and 16' and 17' preferably 30 lie flat upon the face of the portion 15 as shown either in full or in dotted line in Fig. 2. At opposite ends of the portion 16 are portions 25 divided therefrom by scored lines 27, said portions 25 constituting a portion 35 of the ends of the lid when folded or set-up and to connect the portion 16 to the ends of the lid section. The portion 17 is in like manner and for like purpose provided at opposite ends with portions 28 divided from portion 17 by means of scored 40 lines 30.

The sections 31 are folded along the score lines 33 so as to come face to face against the under face of the portion 15 and to form 45 therewith the end portions 32 of the extension. The portions 34 fold along the scored lines 35 and extend outwardly at substantially right angles from the portion 15 when the lid is folded as shown in Fig. 5, but lie preferably in the same plane with 50 portions 15 and 31, as shown in Fig. 2, when being shipped knocked-down.

In the folded or set-up position portions 36 are folded along the scored lines 38, so 55 as to lie face to face against the end portions 34 with a pair of portions 25 and 28 embraced and locked between the adjacent faces of portions 34 and 36. Cuts or slots 60 37 are provided along a portion of the scored lines 35 and the tongues or portions 39 are provided with slits to form locking bars or tongues 39'. The tongues 39 are folded along the scored lines 40 and introduced through the cuts or slots 37 so as 65 to lie face to face upon the inner or under

side of the portion 15 and to key or lock the end and side portions of the lid section into position shown in Fig. 5, substantially at right angles to the portion 15. As illustrated in Figs. 6, 7, and 14 the 70 tongues 39 are drawn through the slots 37 tightly and firmly into position whereupon the tongues 39' acting as barbs or locking members enter between the sections 31 and the section 15 so as to prevent retraction 75 of the tongues 39 through the slots 37 except by practically tearing away the tongues 39. The effect of this locking of the tongues 39 in place is to greatly add to the strength of the boxes particularly when 80 charged with candy, soap or other relatively heavy articles, so as to prevent the weight of the contents from distorting or unlocking the boxes, and also to prevent the boxes being crushed by the exterior pressures. In 85 the knock-down position shown in Fig. 2, the various end portions 31, 34, 36 and 39 preferably lie in a plane with portion 15. In practice the blanks shown in Fig. 1 as soon as they have been printed and blanked 90 out are passed endwise through a gluing or pasting machine and glue or paste indicated at 16' and 17' and at 26 by shading is applied to the portions 16' and 17' and to 95 portions 18 and 19 or to the parts of portion 15 to be overlapped thereby and after folding sections 16' and 17' upon sections 16 and 17, the blanks are then promptly folded to the position shown in full lines 100 Fig. 2, preferably by the pasting machine. If desired the end portions 31, 34, 36 and 37 may be folded in upon the portion 15, along the scored lines 33, before the portions 18 and 19 are glued down to portion 15, but the blanks are preferably shipped 105 knocked-down as shown in full line Fig. 2.

For full telescopic extension boxes, blanks for the lower or container sections, 43, similar to Figs. 1 and 2, but of slightly smaller dimensions, so as to telescope into the lid sections 42, are provided, and are folded as heretofore described for the lid sections. The side extensions 24 formed by gluing the portions 18 and 19 down upon the edges of the portion 15 serve to greatly strengthen 110 and stiffen the respective box sections, also the interengaging folding and locking of the ends of the side portions with the end portions serve to produce firm and rigid box sections equal in strength to the stayed or non-folding box sections heretofore in use. 115

Where it is desired to produce shoulder boxes or partially telescopic boxes two duplicate box sections 45 and 46 are formed by folding as heretofore described from 120 blanks such as shown in Figs. 1 and 2, of equal dimensions. A folding skeleton box frame or collar 47, shown in Fig. 3, is also provided and inserted into the container box section 46 and if desired secured thereto by 125 130

means of glue or otherwise, while the section 45 serves as a lid and telescopes over the projecting portion of the frame 47.

A grade of paper stock having both faces 5 alike and of such strength as to make smooth folds along the scored lines is preferably employed, and such boxes may be employed for general purposes with a uniform flat color or printed design and without having 10 an outer facing paper applied to them after being folded. For general purposes any colors, designs, trade marks, printing or engraving desired may be applied directly to the flat blanks before folding. Where it 15 is desired however to produce special or high grade boxes such as employed for certain grades of candies and toilet articles, many of which are highly ornamented and colored, and are designed to bear the trade 20 marks, advertising matter and insignia of the manufacturers of their contents, it is designed that the boxes in knock-down condition Fig. 2, be shipped from the box manufacturer to the manufacturer of the contents, in whose place of business the boxes 25 are folded or set up, and are then and thereafter faced exteriorly by applying a sizing and facing sheets or strip of paper of such color, or bearing such designs printing, or engraving as may serve to, produce 30 a pleasing and artistic effect and identify the contents of the box with the manufacturer thereof.

It is designed to print the blanks, on 35 one or both sides in their flat condition in a variety of solid colors and pattern designs, and to so form the extensions as to provide smoothly rounded edges and unbroken color at the outer extremity of the 40 extensions, and to so match the cut edges of the blank at the corners, preferably by a miter-type of joint 22 as to avoid exposing cut edges of different color to that of the faces of the extension, and also to give 45 the same miter-joint appearance as in the stayed type of boxes.

Where so desired I contemplate furnishing blanks for folding extension boxes to be shipped in flat condition and folded and set 50 up either with or without the addition of facing paper, at the factory of the box maker or at the factory of the manufacturer of the contents of the box.

It frequently happens that relatively wide 55 boxes are required, as for instance handkerchief boxes, and in Fig. 11, I have illustrated the use of two locking tongues 50 and 51 at each end of the box in place of a single locking tongue as shown in Fig. 1. Each 60 of said tongues 50 and 51 has a slit 52 cut therein to thereby form a tongue or barb 53 corresponding to the barbs 39' of Fig. 1, to lock the tongues 50 and 51 in their set-up positions. The employment of two 65 tongues 50 and 51 on relatively wide boxes

serves to better hold the members 34, 25, 28 and 36 in close contact face to face with each other. In the modification shown in Fig. 12, which is also designed to be applied to relatively wide boxes, a central tongue 70 54 is employed at each end and provided with a barb 55 to lock it in its set-up position after the tongue 54 has been inserted through the central slit 56. Also at each end of the blank are provided additional 75 slits 57 and 58 in line with and at opposite sides of the slit 56, and short projections 59 and 60 to automatically register with and resiliently and automatically enter the slits 57 and 58 as the tongue 54 is drawn home 80 to lock the box in its set-up position.

It will be noted that while means previously employed to lock folding boxes is not adapted to the production and locking of relatively shallow boxes such as employed 85 as handkerchief boxes for instance, due to want of space for the development of locking means, my improved locking means does not require any specific depth of box—for its application, and can be successfully applied to exceedingly shallow boxes where required. Also that when the box is once set-up and locked it is practically impossible to unlock it and return it to its knocked-down condition, and hence that it is not liable 90 to become accidentally unlocked in use so as to lose its contents, thereby insuring a folding box of equal strength and rigidity with the stayed boxes heretofore employed 95 for candy, soap, and other articles of material weight.

It will also be noted that my improved locking means provides at least two unbroken thicknesses of material at each end 100 to insure rigidity at the ends of the box 105 while the side sections 16' and 17' in connection with the side sections 16 and 17 provide side walls of double thickness of material thereby reinforcing the side-walls of the box to equal rigidity with that of its 110 ends. The box with end and side walls of double thickness and when rigidly locked in its set-up position is sufficiently rigid for all ordinary purposes, such as use for candy, shoe, and soap boxes for instance. Where 115 it is desired to reinforce the bottoms and tops of the boxes to double thickness, or to improve the interior finish or appearance I provide separate sections of card-board 120 125 of nearly the same length as the sections 15 and of somewhat greater width, which members 62 are scored at the sides along the lines 63 and 64. These sections 62 are adapted to be inserted into the box and lid members after said box and lid members have 130 been set-up, and when so inserted and pressed into contact with the inner face of the sections 15 and the exposed faces of the tongues 39, the edges 65 and 66 of said sections 62 enter beneath the edges 67 and 68

of the sections 16' and 17' as shown in Fig. 8 to firmly lock the sections 62 in position to conceal the tongues 39, and to reinforce the top and bottom of the box or either of them to double thickness. I am thus enabled to produce folding boxes from practically the same blank of progressively different degrees of rigidity according to the service required, and to ship the blanks in the flat condition, to be set up where required for use, and of various sizes up to suit boxes or larger if required.

The articles herein illustrated and described are capable of considerable modification without departing from the principle of my invention.

What I claim is:

1. A blank for a folding box section to constitute a box lid or a box container comprising a main portion, to form the top or bottom of a box, a plurality of portions connected to the side and end margins of said main portion and adapted to be folded upon one of the faces of said main portion to form an extension margin, a pair of side wall portions connected to the outside margin of the portions to be folded in upon the main portion at its sides and provided with end extensions at opposite ends of said side wall portions to fold inwardly and interengage with the end wall portions, end wall portions connected to the outer edges of the portions to be folded upon the face of the main portion at its ends, said end wall portions each comprising a section to engage the inner face of an end extension of each side wall portion, a section to engage the outer face of an end extension of each side wall portion, a slit near the base of said end portion, a locking tongue to enter said slit and a locking member carried by said tongue to prevent retraction of said tongue, said tongue and locking member serving to positively lock said side wall portions and end wall portions together in set-up position.

2. A blank for folding box section to constitute a box lid or box container comprising a main portion to form the top or bottom of a box, a plurality of relatively narrow portions connected to the outer margin of said main portion and adapted to be folded upon one of the faces of said main portion to form an extension margin, side wall portions at the outer sides of said relatively narrow side portions provided with end extensions extending past the ends of said main portion and adapted to be folded inwardly to interengage with end portions, end wall portions connected to the relatively narrow portions at the ends of said main portion, each of said end portions comprising a section to engage the inner face of an end extension from each of said side wall portions, a section to engage the outer face of an end extension from each of said side

wall portions, a slit near the base of said end portion, a locking tongue to enter said slit, and a locking member carried by said tongue to prevent retraction of said tongue, said tongue and locking member serving to positively lock said side wall portions and end wall portions together in set-up position.

3. A one piece folding blank for extension box sections to constitute a box lid or box container, comprising a main portion having relatively narrow extension portions at its opposite sides folded over upon one face of said main section and attached thereto, main side wall portions having reinforcing side wall portions folded over upon and attached to said main side wall portions to form finished side wall edges and reinforced side walls, said side wall portions having extensions separated therefrom by score lines and said wall portions and their extensions being adapted to occupy a plane substantially parallel to and at one side of said main portion, and end wall portions at opposite ends of and in substantially the same plane with said main portion, each of said end wall portions being subdivided by score lines and a slit into two end wall members and a locking tongue, to lock said side wall and end wall portions together when set up.

4. A one piece folding blank for extension box sections to constitute a box lid or box container, comprising a main portion having relatively narrow extension portions upon opposite sides folded over upon one face of said main section and attached thereto, side wall portions attached to said extension portions having end extensions separated therefrom by score lines, said side wall portions occupying a plane substantially parallel to and at one side of the plane of said main portion, and end wall portions at opposite ends of and in substantially the same plane with said main portion, each of said end wall portions being subdivided by score lines and slits into two end wall members, a locking tongue and a barb to lock said side wall and end wall portions together when set-up and to retain said tongue in locked-position.

5. A blank for a folding box section to constitute a box lid or box container comprising a main portion, side wall portions at the sides of said main portion provided with end members extending past the ends of said main portion, end wall portions at the ends of said main portion comprising two end wall members, a locking tongue and a barb to prevent retraction of said tongue separated by score lines and slits, the end wall members adjacent to the main portion being folded inside of the end members of the side wall portions, and the outer end wall members being folded outside of the end

members of the side wall portions and the locking tongue and barb inserted through slits in the end wall portions to lock the end and side wall portions together and to prevent accidental retraction of said tongues after being set up into a box section.

6. A blank for a folding box section to constitute a box lid or box container comprising a main portion, main side wall portions, reinforcing side wall portions to be folded in upon the face of said main side wall portions, said side wall portions being provided with end members extending past the ends of said main portion, end wall portions at the ends of said main portion comprising two end wall members and a locking tongue separated by score lines and slit, the end wall members adjacent to the main portion being folded inside of the end members of the side wall portions and the locking tongues inserted through said slits to lock the end and side wall portions together when the blank is set up into a box section.

7. A blank for a folding box lid or box container comprising a main portion, side wall portions at the sides of said main portion provided with end members extending past the ends of said main portion, end wall portions at the ends of said main portion comprising two end wall members and a locking tongue separated by score lines and a slit, the end wall members adjacent to the main portion being folded inside of the end members of the side wall portions, and the outer end wall members being folded outside of the end members of the side wall portions, and the locking tongues inserted through said slits to lock the end and side wall portions together when the blank is set up into a box section, and means to prevent the retraction of said tongues after said box sections have been set-up.

8. A blank for a folding box section to constitute a box lid or box container comprising a main portion, main side wall portions, reinforcing side wall portions to be folded in upon the face of said main side wall portions, said side wall portions being provided with end members extending past the ends of said main portion, end wall portions at the ends of said main portion comprising two end wall members and a locking tongue separated by score lines and a slit, the end wall members adjacent to the main portion being folded inside of the end members of the side wall portions and the outer end wall members being folded outside of the end members of the side wall portions, and the locking tongues inserted through said slits to lock the end and side wall portions together when the blank is set up into a box section, and means to prevent the re-

traction of said tongues after said box sections have been set-up.

9. A blank for a folding box section to constitute a box lid or box container comprising a main portion, a plurality of portions connected to the side and end margins of said main portion and adapted to be folded upon one of the faces of said main portion to form an extension margin, a pair of side wall portions connected to the outside margin of the portions to be folded in upon the main portion at its sides and provided with end extensions at opposite ends of said side wall portions to fold inwardly and interengage with end wall portions, end wall portions connected to the outer edges of the portions to be folded upon the face of the main portion at its ends, said end wall portions each comprising a section to engage the inner face of an end extension of each side wall portion, a section to engage the outer face of an end extension of each side wall portion and a plurality of locking members to enter slits at the base of said respective end wall portions to hold the respective sections of the respective end wall portions at frequent intervals in close contact with the end extensions of the side wall portions, and one or more barb members to prevent disengagement of said locking members.

10. A blank for a folding box section to constitute a box lid or box container comprising a main portion to form the top or bottom of a box, a plurality of relatively narrow portions connected to the outer margin of said main portion and adapted to be folded upon one of the faces of said main portion to form an extension margin, side wall portions at the outer sides of said relatively narrow side portions provided with end extensions extending past the ends of said main portion and adapted to be folded inwardly to interengage with end portions, end wall portion connected to the relatively narrow portions at the end of said main portion, each of said end portions comprising a section to engage the inner face of an end extension from each of said side wall portions, a section to engage the outer face of an end extension from each of said side wall portions, slits at frequent intervals near the base of said end portions, a plurality of locking tongues to enter said slits, and locking members carried by said tongues to prevent retraction of said tongues, said tongues and locking members serving to positively lock said side wall portions and end wall portions together in set-up position.

11. A blank for a folding box section to constitute a box lid or box container comprising a main portion, side wall portions at the sides of said main portion provided with end members extending past the ends of said main portion, end wall portions at the

- ends of said main portion each comprising two end wall members, a plurality of tongues adapted to lock said end wall members together at frequent intervals and to prevent retraction of said tongues separated by score lines and slits, the end wall members adjacent to the main portion being folded inside of the end members of the side wall portions, and the outer end wall members 10 being folded outside of the end members of the side wall portions and the locking tongues inserted through slits in the end wall portions to lock the end and side wall portions together and to prevent accidental 15 retraction of said tongues after being set up into a box section.

12. A blank for a folding box section to constitute a box lid or a box container comprising a main portion to form the top or 20 bottom of a box, a plurality of portions connected to the side and end margins of said main portion and adapted to be folded upon one of the faces of said main portion to form an extension margin, a pair of side 25 wall portions connected to the outside margins of the portions to be folded in upon the main portion at its sides and provided with end extensions at opposite ends of said side wall portions to fold inwardly and interengage with end wall portions, end wall portions connected to the outer edges of the portions to be folded upon the face of the main portion at its ends, said end wall portions each comprising a section to engage the 30 inner face of an end extension of each side wall portion, a section to engage the outer face of an end extension of each side wall portion, and a locking tongue to enter a slit at the base of said respective end portions 35 to positively lock said side wall portions and end wall portions together.

13. A blank for folding box section to constitute a box lid or box container comprising a main portion to form the top or bottom 40 of a box, a plurality of relatively narrow portions connected to the outer margin of said main portion and adapted to be folded upon one of the faces of said main portion to form an extension margin, side wall portions 45 at the outer sides of said relatively narrow side portions provided with end extensions extending past the ends of said main portion and adapted to be folded in-

wardly to interengage with end portions, end wall portions connected to the relatively narrow portions at the ends of said main portion, each of said portions comprising a section to engage the inner face of an end extension from each of said side wall portions, a section to engage the outer face of an end extension from each of said side wall portions, and a locking tongue to enter a slit at the base of said respective end portions to positively lock said side wall portions and end wall portions together when set up to 65 resist weight and pressure from the contents of the box.

14. A one piece folding blank for extension box sections to constitute a box lid or box container, comprising a main portion 70 having relatively narrow extension portions at its opposite sides, folded over upon one face of said main section and attached thereto, side wall portions having end extensions separated therefrom by score lines, said side wall 75 portions occupying a plane substantially parallel to and at one side of the plane of said main portion, and end wall portions at opposite ends of and in substantially the same plane with said main portion, each of said end wall portions being subdivided by score lines and a slit into two end wall members and a locking tongue to lock said side wall and end wall portions together when set up.

15. A blank for a folding box section to 80 constitute a box lid or box container comprising a main portion, side wall portions at the sides of said main portion provided with end members extending past the ends of said main portion, end wall portions at the ends 85 of said main portion comprising two end wall members and a locking tongue separated by score lines and a slit, the end wall members adjacent to the main portion being folded inside of the end members of the side wall 90 portions, and the outer end wall members being folded outside of the end members of the side wall portions, and the locking tongues inserted through slits in the end wall portions to lock the end and side wall 100 portions together when the blank is set up into a box section.

In testimony whereof I have affixed my signature.

CHARLES B. HOY.
